UNITED STATES PATENT OFFICE.

WARREN H. TAYLOR, OF STAMFORD, CONNECTICUT, ASSIGNOR TO THE YALE & TOWNE MANUFACTURING COMPANY, OF SAME PLACE.

LOCK.

SPECIFICATION forming part of Letters Patent No. 380,537, dated April 3, 1883.

Application filed November 14, 1887. Serial No. 255,089. (No model.)

To all whom it may concern:

Be it known that I, WARREN H. TAYLOR, of Stamford, in the county of Fairfield and State of Connecticut, have invented a certain new and 5 useful Improvement in Locks, of which the following is a specification, reference being had to the accompanying drawings.

My invention relates particularly to that class of locks in which the tumblers are contained in a separate escutcheon or tumbler-case—such, for instance, as the well-known Yale locks; and it has for its object the prevention of the removal of this escutcheon or tumbler-case, except by one who is in possession of the key for 15 unlocking the lock, and who, therefore, may be presumed to have the right to remove the escutcheon. The usual method of fastening an escutcheon in place is by means of a set-screw passing through the face of the lock and engaging with a groove or other depression in 20 the periphery of the escutcheon, so that when the set-screw is turned out the escutcheon can be removed. There are also other methods of fastening in the escutcheon; but heretofore 25 locks have been so constructed that when the door was open and the face-plate accessible any person with a screw-driver or the point of a knife could release the set-screw or other stop, so that the escutcheon could be un- 30 screwed or otherwise removed. If such person desired to effect an entrance to the room or house, he could release the set-screw or other stop sufficiently, so that while the turning of the key to throw the bolt would not turn the 35 escutcheon, the escutcheon could be turned by the application of slight force. Then, after the owner had left the door locked, as he supposed, the evil-disposed person could return and unscrew the escutcheon, or otherwise re- 40 move it, and have access to the interior of the lock, so that he could unlock it. My invention removes this source of weakness and provides a fastening for the escutcheon in the interior of the lock which can only be released 45 by means of the proper key acting through the escutcheon itself. It is evident that if any one has the proper key to the lock he can gain access to the room, and so will have no object, except a proper one, in removing the escut- 50

My invention consists in the special means of fastening an escutcheon within the interior of a lock, as hereinafter specified, and succinctly summed up in my appended claim.

In the accompanying drawings, Figure 1 is 55 a view of a lock containing my improvement, one plate of the lock being removed; and Fig. 2 is a detail view of my invention detached from a lock.

Referring to the letters upon the drawings, 60 A indicates a lock-case, B a lock-bolt, and C a screw-threaded escutcheon set into the case in the usual way.

D indicates a set-screw, and E a forked slide adapted to enter the grooves in two opposite 65 escutcheons and hold them in place.

The devices thus far described are all old.

Coming to what is new, I provide the ordinary set-screw fastening, F, and on it a projection, G.

H indicates a bell-crank lever pivoted at I, and serving to throw the bolt into the unlocked position against its spring when it is operated by means of the ordinary cam, K, upon the key-hub X, as will be obvious from the drawings. This bell-crank is provided with a shoulder, L, which engages with the projection G, forming a latch-connection, thus securely dogging the set-screw fastening. This bell-crank lever is provided with a spring, M, which tends 70 to keep it all the time in the position indicated by the full lines in Fig. 2, in which position it is latched with the projection G upon the set-screw fastening for the escutcheon. When the key is inserted and the hub turned, it will 75 release the latch-connection and throw the bell-crank lever into the position shown by the dotted lines in Fig. 2, and thus release the set-screw fastening of the escutcheon, so that it can be withdrawn and the escutcheon removed. 80

At all other times the spring will keep the bell-crank lever latched with this projection of the set-screw fastening, so that it cannot be withdrawn and the escutcheon cannot be removed; hence it becomes impossible to release and withdraw the escutcheon, except by the use of the key to unlatch the internal set-screw fastening.

This invention is adapted to be used with numerous varieties of locks having escutcheons or tumbler-cases of similar nature.

100

In the drawings are shown several ordinary parts of a lock which I do not describe, because they form no part of this invention.

I have taken out a United States Patent No. 5 373,253, in which I show several varieties of devices of this general nature for securing escutcheons in place, and in which I have made a broad claim, and I therefore do not claim in the present case more than the peculiar device 10 herein described, which is not specifically claimed in said patent.

I claim—

The combination, in a lock having an escutcheon and set-screw fastening therefor, of a projection, G, on the set-screw fastening, a 15 spring-actuated bell-crank lever, H, and a shoulder, L, on the bell-crank, forming a latch-connection, substantially as set forth.

In testimony whereof I have hereunto subscribed my name:

WARREN H. TAYLOR.
